UNITED STATES PATENT OFFICE.

GEORGE H. WILKINS, OF GREENFIELD, MASSACHUSETTS, ASSIGNOR TO GEORGE H. WILKINS COMPANY, OF CHICAGO, ILLINOIS, A CORPORATION OF ILLINOIS.

DEVICE FOR FILLING PIPE-JOINTS.

1,226,043.

Specification of Letters Patent.

Patented May 15, 1917.

Application filed December 14, 1916. Serial No. 136,880.

To all whom it may concern:

Be it known that I, GEORGE H. WILKINS, a citizen of the United States of America, residing in the city of Greenfield, county 5 of Franklin, and State of Massachusetts, have invented certain new and useful Improvements in Devices for Filling Pipe-Joints, of which the following is a specification.

10 This invention relates to improvements in devices for running or filling pipe joints, particularly for directing the flow of molten material, as lead into the annular space between the spigot and bell end of two adjoining pipes. This invention relates to the 15 type of devices shown in the United States Patent granted to F. J. Hatch, No. 948,686, dated Feb. 8, 1910, in which a rope or flexible packing belt is tightly clamped about 20 the spigot end of a pipe section and close to the bell end of the adjacent pipe section; the clamping means being provided with a spout-like structure for directing the flow of 25 the molten material to the joint inside of the rope, the rope serving the purpose of preventing the molten material from escaping from the annular chamber in the bell.

The present invention, broadly, comprises 30 two rope clamping members which are pivoted together intermediate of their ends, one end engaging the rope and the other adapted to be grasped by the operator to 35 open the clamp, whereby the rope can be readily inserted and drawn around the pipe tightly. The clamps are automatically forced 40 against the rope by means of a spring, thus binding it tightly to the pipe. The present device is one that can be readily formed by stamping or die work and is one that can be constructed at a low cost.

Referring to the drawings:

Figure 1 is a perspective view showing the device in use with the rope clamped between the plates thereof, and illustrating the pouring spout, the lower end of which lies within the meeting ends of the rope at the upper side of the pipe;

Fig. 2 is a perspective view with the rope 50 removed showing the manner of pivotally connecting the clamping plates together, also the spring, the opposite ends of which

are attached to the handle part of the plates and the spiral or coil intermediate of its ends and located back of the connecting arms of the plates.

55

Referring to the drawings in detail: 1 designates the bell-end 2 the spigot end of two pipe sections. 3 is the packing rope, preferably composed of asbestos or some suitable composition that is flexible and that 60 will withstand high temperatures. This rope is passed around the pipe 2 and in contact with the collar 3'. The free ends 4 and 5 of the rope pass upward between the clamping surfaces 6 and 7 of the plates 8 65 and 9. These plates are formed with inwardly extending arms 10 and 11 for the purpose of pivotally attaching the plates together by means of the pivot shown at 12. A stop 13 is secured to a part of arm 10 70 and serves as a limiting stop for the overhanging lip 14 which lip is preferably made integral with the part 10 which passes behind the arm 11 and upward and then over the top of the arm 11 and then downward as 75 shown. This stop device limits the inward movement of the lower ends 6 and 7 in order to permit the rope 3 to be inserted without having to move these ends through a long arc, as would be the case if the stop device 80 did not hold them separated against the action of the operating spring. When the rope is in place, as shown in Fig. 1 the spring then exerts its force on the rope. In order to normally force the rope clamping 85 plates 6 and 7 inward and toward each other, which are located at the lower ends of the arms 8 and 9, a stiff spring having a coil 15 intermediate of its length is attached to the arms 8 and 9 at their upper ends by means 90 of the extensions 16 and 17 which are passed through openings in the upper ends of these arms, as shown. Formed integral with the plates and arm 8 is the inclined pouring spout or mouth portion 18 which is connected to the clamping surface 6 by means 95 of the neck portion 19. Integral with the portion 18 is the downwardly extending triangular shaped end or side plate 20, the lower horizontal edge 21 of which rests upon the pipe 2, when in use, as shown in Fig. 1.

It will be seen that the curved surface 18

which is located between the neck portion 19 and the triangular portion 20 is inclined to the horizontal plane so that the molten material when it is poured into the upper end of the inclined pouring spout or mouth portion 18 readily flows downward to the lower end where it escapes into the space 22 that is formed between the ends 4 and 5 of the rope. This opening 22 readily directs the flow of the molten material to the annular space in the bell of the pipe 1 and where it can flow to completely fill this space without any of it escaping since the rope 3 is tightly clamped around the pipe 2 and against the bell. The lower end of the portion 18 is slightly cut away, as indicated at 23, in order that there may be no clogging of the molten material at this point and to permit the spout to closely fit the pipe. It will be observed that the upper ends of the arms 8 and 9 are extended to form enlarged flat hand gripping surfaces 24 to enable the operator to more readily grasp the device when inserting the rope and releasing the same. It will be observed that the length of the clamping arms 6 and 7 as indicated on the line 25, is such that there is plenty of surface or space between the outer edges 26 of these arms and the angular extending portions 10 and 11, whereby the entire width of the ends 4 and 5 of the rope are securely clamped as reference to Fig. 1 will clearly show or, in other words, the distance that these clamping plates 6 and 7 extend outward is substantially equal to the width of the rope 3.

What I claim is:

1. A device of the class described, comprising in combination, clamping members 40 pivotally connected together, each member being formed with a clamping surface for engaging the rope that is designed to be drawn around the outer surface of a pipe, a pouring spout connected to a member for directing the flow of molten material into the space between the meeting ends of the rope, and means for normally forcing the clamping plates toward each other.

2. In a device of the class described, the combination, of substantially parallel members, means for pivoting the members together, a stop device for limiting the inward movement of the lower ends of said members toward each other, said members having clamping surfaces for holding the ends of a rope together, one member having a spout formed at the lower end thereof to direct the flow of the molten material.

3. In a device of the class described, the combination with a pair of clamping members, means for pivoting the members together, a stop device for limiting the movement of the members toward each other, said members having clamping surfaces to receive a rope, one member having a pour-

ing spout to direct the flow of molten material.

4. A device of the class described, comprising clamping members, said members being pivotally connected together, the lower ends of which are formed with plates for receiving a flexible packing or the like which is designed to be placed around the spigot end of a pipe section and close to the bell end of an adjacent pipe section for confining the flow of molten material, a pouring-spout integral with one of the clamping plates, and located so as to direct the flow of the material through the rope and into the annular chamber surrounding the spigot end of a pipe, said pouring-spout being formed so as to conform to the upper surface of the spigot end of a pipe, and means for moving the clamping plates toward the rope so as to engage the opposite outer surfaces of the rope.

5. A device of the class described, comprising a pair of plates each having an arm for pivotally securing the same together, a stop device for limiting the movement of the plates toward each other, a spring attached to the plates for forcing the plates toward each other, one of the plates having an inclined spout connected thereto and the outer side of the spout being substantially triangular in form, its lower edge being designed to rest upon the spigot end of the pipe.

6. In a device of the class described for directing the flow of molten material to the annular space surrounding the spigot end of a pipe section and within the surface of the bell end of the adjacent pipe section and comprising plate members designed to clamp a rope which is located around the spigot end of one of the pipes, the pouring spout being inclined and its lower end terminating at a point near the ends of the rope, and means for forcing the plates toward each other for clamping said rope.

7. In a device of the class described, comprising a pair of clamping plates pivotally secured together, a spring for forcing the plates normally toward each other one of the plates having a pouring spout connected thereto and arranged on an angle to the horizontal plane, the outer side of the spout being designed to rest upon the upper side of the spigot end of a pipe and the lower end of the spout being cut away so as to fit the pipe, as described.

8. A device of the class described comprising plates, having clamping surfaces, a pouring spout connected to one of the plates, means for connecting the plates together and means for forcing the plates toward each other to clamp a flexible packing rope.

9. A device of the kind described comprising a pair of pivotally connected plates formed with clamping surfaces, a spring

for forcing the plates toward each other, and an inclined pouring spout connected to one of the plates.

10. A device of the kind described having in combination a pair of pivotally connected plates for clamping a flexible rope, means for forcing the plates toward each other, a

pouring spout arranged between the plates, one side of the spout being connected to one plate and its opposite side being connected to a part which engages the spigot end of the pipe when in use. 10
